FIG. 10.

UNITED STATES PATENT OFFICE.

WILLIAM H. SAUVAGE, OF DENVER, COLORADO, ASSIGNOR TO CHRESTUS A. TRIPP, OF SALT LAKE CITY, UTAH.

SLACK-ADJUSTER.

SPECIFICATION forming part of Letters Patent No. 704,970, dated July 15, 1902.

Application filed October 25, 1901. Serial No. 79,960. (No model.)

To all whom it may concern:

Be it known that I, WILLIAM H. SAUVAGE, a citizen of the United States of America, residing at Denver, in the county of Arapahoe and State of Colorado, have invented certain new and useful Improvements in Slack-Adjusters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in slack-adjusters for car-brakes, or means for automatically maintaining the brake-shoes at a uniform predetermined distance from the car-wheels.

20 I do not need to emphasize the fact that the present usual method, or so-called "hand-adjustment" of brake-shoes, (on freight-cars particularly,) is at best not very satisfactory. This is plain and fully verified by simply

25 noting the adjustment of such equipment at any place at any time on any railroad. It is believed that fully ninety per cent of such cars (carefully inspected) will likely be found with much more slack than is desirable unless it be such as have just been provided

30 with new shoes or where slack has just been taken up by hand. The same conditions are found on passenger equipment, though, perhaps, not to such an aggravated degree.

35 The cost of railroad companies in time expended by train-crews or others making frequent or even occasional adjustments is of much importance, to say nothing of the cost in the way of damage and, perhaps, loss of life

40 occasioned by wrecks, &c., by reason of improper or inadequate adjustments of brake-shoes, piston travel, and general inefficiency of air-brake mechanism. Automatic regulation of brake-shoes, and thereby incidentally regulating air-brake piston travel, is one of the important subjects of the day in connection with air-brake service.

45 It is evident that no present arrangement of air-brake mechanism can fulfil its mission with loose brake-shoes and long piston travel.

To restrict piston travel close to a given limit

will undoubtedly give increased efficiency to present air-brake mechanism and save expense by using less air to accomplish a given amount of work. This cannot be accomplished with a piston on some cars having ten or eleven inches travel, on others perhaps less, and on a few at or about the proper limit. Uniform piston travel is an important feature of good brake service, and this very desirable result cannot be had from present hand adjustments, but if it can be maintained automatically on each car and at all times it insures greater safety, and consequently higher speed and the greatest possible efficiency of all the brakes thus automatically adjusted. With hand adjustment the piston travel will change with each succeeding brake application with correspondingly decreasing efficiency of braking power.

55 My present invention consists of certain improvements in the construction set forth in my previous patent, dated February 18, 1902, and numbered 693,806, which improvements will now be described in detail, reference being made to the accompanying drawings, in which is illustrated an embodiment thereof.

60 In the drawings, Figure 1 illustrates my improvement shown in connection with a set of ordinary brake appliances. In this view the axles and bolster are shown in cross-section and the other parts in side elevation, the construction being arranged for "outside" connected brake-shoes. Fig. 2 is a fragmentary view showing the brake-levers in horizontal section. Fig. 3 is a view similar to Fig. 1, the mechanism being arranged for "inside" connected brake-shoes. Fig. 4 is a fragmentary side elevation showing the dead truck-lever in connection with the ratchet-bar and its co-operating dog. Fig. 5 shows the same parts viewed at right angles to Fig. 4, the parts being shown in section. Fig. 6 is a top view of the same. Fig. 7 is a section taken through the hollow bar and its telescoping part, showing one form of clamp applied to the hollow bar. Figs. 8 and 9 show another form of clamp. Fig. 10 is a fragmentary plan view of the Westinghouse air-brake construction, showing the release-springs employed in connection with my slack-adjusting mechanism.

The same reference characters indicate the same parts in all the views.

Let the numeral 5 designate the brake-beams; 6, the shoes; 7, the dead truck-lever; 8, the live truck-lever; 9, the top rod; 10, the bottom rod, and 12 the car-wheels.

The brake-levers 7 and 8 are connected by a rod 13, attached to one lever and arranged to telescope in a tube or hollow bar 14, attached to the other lever. As shown in the drawings, the bolt 15, which connects the lever 7 with the brake-beam, passes through a slot 13^a, formed in the flattened extremity of the rod 13. The bar 14 is provided with an opening in one extremity, through which passes the bolt 16, which connects the lever 8 with the adjacent brake-beam. The free extremity of the rod 13 enters a longitudinal opening formed in the bar, in which the rod 13 telescopes. The extremity of the bar 14 is slotted, as shown at 14^c, and surrounded by a clamping-collar 17, which is provided with an eyebolt 18, whose eye passes between the jaws of a cam-lever 18^a for convenience of adjustment. By use of this clamping device the rod 13 may be made to fit the opening in the hollow bar in such a manner that while the rod when actuated by the braking force is allowed to enter the bar and take up the slack the rod will retain its position in the bar when the brakes are released.

Another form of clamp is shown in Figs. 8 and 9 and consists of a piece of spring-steel A, shaped to clasp the slotted portion of the tubular bar 14 and normally produce sufficient friction for the purpose. This clamp is provided with an interiorly-projecting lug A', adapted to enter a recess formed in the hollow bar, whereby the clamp is held securely in place. The free extremities A^a of this clamp are opened sufficiently to permit the insertion of a suitable tool when it is desired to spread the clamp or loosen its normal grip on the bar.

The length of the slot 13^a determines the normal distance of the shoes from the wheels when the brakes are released. All the other slack is taken up by the telescopic connection between the brake-shoes composed of the bar 14, rod 13, and the clamping device heretofore described.

To the bolster B or other relatively stationary part of the car is suitably attached one extremity of a ratchet-bar 20, whose opposite extremity 20^a is provided with ratchet-teeth and provided with a vertical central longitudinal slot 20^c, through which the upper extremity of the lever 7 protrudes. Mounted upon the upper extremity of this lever is a dog 19, adapted to engage the ratchet-teeth of the bar. This dog is provided with a downwardly-projecting pin 19^a, passing through the slot of the bar and projecting below its lower edge. The lower extremity of this pin is provided with a key 19^c to prevent the dog from turning or jumping out of place. As shown in the drawings, the ratchet-bar is

pivotedly connected with the bolster and rides on an antifrictional bearing C; mounted on each side of the lever 7.

It will now be understood that in applying the brakes through the instrumentality of an ordinary air-brake system, as the Westinghouse, the rod 9 will be moved toward the left or in the direction indicated by the arrow in Figs. 1 and 3, and both brake-beams will be moved toward the wheels of the car by virtue of the coöperation of the bottom rod 10. When the brakes are released, the bolt 15 engages the outer extremity of the slot 13^a, or the extremity of said slot farther to the left, referring to the drawings. As the brake-beams move toward the wheels the bar 14 will move toward the left or in the direction indicated by the arrow until the extremity of the slot 13^a farther to the right engages the bolt 15. If the brake-shoes are the proper distance from the wheels, as determined by the length of the slot 13^a, the shoes will be in contact with the wheels, and the rod 13 and the bar 14 will act as an integral part. If, however, there is too much slack, or, what is the same thing, if there is still a space between the brake-shoes and the wheels, after the bolt 15 engages the right-hand extremity of the slot 13^a the braking force will act to thrust the rod 13 telescopically into the bar 14 in the construction shown in Fig. 1, or draw it out of the bar 14 in the construction shown in Fig. 3, until the superfluous slack is taken up and the brake-shoes are brought into contact with the wheels. By virtue of the connection between the rod 13 and the bar 14 these parts will be maintained in the adjusted position. Then as the brakes are released the rod 9 will be moved in the opposite direction a corresponding distance; but since the slack is taken up the fulcrum-point of the lever 8 cannot travel back to its original position, the lower arms of the levers 7 and 8 will be thrust toward the left and the upper arm of the lever 7 toward the right, and the dog 19 will hold the ratchet-rod in the adjusted position, thus compensating for the changed relation between the parts, while the rod 13 is maintained in the position heretofore stated, or, in other words, in the position in the bar 14 to which it has been thrust or drawn in taking up the slack of the brake-shoes.

In order to cause the immediate or prompt release of the brake-shoes from the wheels when necessary steps have been taken to release the brakes, I attach a leaf-spring 21 to a needle-beam 22 on the bottom of the car, the arrangement being such that the spring shall bear against the lever 23 (usually termed the "floating" lever) and normally have a tendency to release the brakes at one end of the car. I also attach a similar spring 24 to another beam 22, adjacent the cylinder-lever 25, the arrangement being such that the spring bears against the cylinder-lever and has a normal tendency to release the brakes at the

other end of the car. The springs cause the positive and instantaneous release of the brake-shoes from the wheels of the car at the proper point of time, thus producing a great saving in wear of brake-shoes and a saving of energy in pulling and starting trains. These springs also take up slack, and constitute a very important feature in mechanism of this class.

10 Under the old system it is customary after trains are made up to thoroughly test the air-brakes on all cars before leaving the terminal. This is usually done by the engineer making a full application of air. Inspection of the 15 trainmen follows, and each brake is properly adjusted by hand. With my automatic slack-adjuster the engineer adjusts all of the brakes in the first application, consuming only a few minutes of time, while the old way usually 20 takes a considerable amount of time and labor before the train is ready to leave.

Having thus described my invention, what I claim is—

1. The combination with brake mechanism, 25 of means for automatically retaining the brake-shoes at a predetermined distance from the car-wheels, said means comprising a two-part frictionally-held connection between the brake-beams, a ratchet-bar mounted on a 30 relatively stationary part of the car, and a dog mounted on the dead truck-lever and engaging the teeth of the ratchet-bar, the arrangement being such that as the brakes are released, the dead truck-lever is actuated to 35 compensate for the limit of movement of the live truck-lever, the dog engaging the ratchet-bar to hold the dead truck-lever in the adjusted position.

2. In a slack-adjuster, the combination 40 with a brake mechanism, of a two-part frictionally-held connection between the brake-beams, a ratchet-bar mounted on a relatively stationary part of the car and slotted to receive the dead truck-lever which passes up- 45 wardly therethrough, and a dog mounted on the upper extremity of the said lever and adapted to engage the teeth of the ratchet-bar.

3. In an apparatus of the class described, the combination with brake mechanism, of a 50 two-part frictionally-held connection between the brake-beams, a ratchet-bar mounted on a relatively stationary part of the car, and slotted to receive the dead truck-lever which passes upwardly therethrough, a dog mounted 55 on the upper extremity of the said lever and engaging the teeth of the ratchet-bar, the dog being provided with a pin projecting downwardly through the slot of the ratchet-bar, and a device attached to said pin below 60 the bar to prevent displacement of the dog.

4. In a slack-adjuster for car-brakes, the combination with brake mechanism, of a two-part frictionally-held connection between the brake-beams, a ratchet-bar mounted on a relatively 65 stationary part of the car and slotted to receive the dead truck-lever which passes upwardly therethrough, the lever being provided with an antifrictional support for the ratchet-bar, and a dog mounted on the upper 70 extremity of the said lever and adapted to engage the teeth of the ratchet-bar, substantially as described.

5. In a slack-adjuster, the combination with brake mechanism, of a two-part frictionally-held connection between the brake-beams, a ratchet-bar mounted on a relatively 75 stationary part of the car and slotted to receive the dead truck-lever which passes upwardly therethrough, a dog mounted on the 80 upper extremity of the said lever and adapted to engage the teeth of the ratchet-bar, and means mounted on a relatively stationary part of the car, and engaging the levers of the air-brake system, to facilitate the prompt release 85 of the brake-shoes and the necessary adjustment of the truck-levers, to compensate for the changed relation of the parts incident to taking up the slack during the 90 brake-setting operation.

In testimony whereof I affix my signature in presence of two witnesses.

WILLIAM H. SAUVAGE.
